APPARATUS FOR ANNEALING

Harold Olcott Shepard, Pittsburgh, Pa., assignor
to United Engineering and Foundry Company,
Pittsburgh, Pa.

Application May 27, 1940, Serial No. 337,372

11 Claims.

(Cl. 266—3)

This invention relates to apparatus for heat treating of metal, and more particularly for the heat treatment of aluminum strip and material of like character.

In heat treating certain metals it is desirable to heat the metal to a temperature which is nearly as high as the temperature at which the tensile strength of the metal practically disappears. Duralumin, for example, loses substantially all of its tensile strength by the time it reaches a temperature of 966° F., but to increase its ultimate strength it should be heated to a temperature from about 932° to 950° F. and then quenched in a liquid. Due to the loss in tensile strength of such material at such high temperatures, difficulty has been encountered in heat treating it in the usual manner in continuously moving strip form, which has many advantages, because the tension that has heretofore been exerted on it is quite likely to tear it apart.

It is among the objects of this invention to provide apparatus for the heat treatment of continuously moving metal strip at any desired temperature without danger of it separating, which apparatus is compact and which obtains the maximum heating effect for its size.

In accordance with this invention continuously moving metal strip is carried through a heating chamber by supporting means which travels with the strip so as not to put the strip under tension. Consequently, while the strip is being carried in this manner it can be heated to a temperature at which its tensile strength is materially reduced without danger of its being pulled apart. When the heated strip finally leaves its carrier it is immediately cooled in order to re-establish its tensile strength so that it will not separate when appreciable tension is placed on it again. For this purpose the cooling means engages the strip substantially at the point at which it leaves the carrier in the heating chamber. Preferably, the carrier comprises a heated drum to which the strip is fed at substantially its lowest point and which it leaves after it has traveled more than three-fourths of the way around the circumference of the drum. The cooling means most suitably is a roll which holds the strip against the drum and around which it is led away from the drum to a tank containing the desired cooling liquid.

The preferred embodiment of apparatus constructed in accordance with my invention is illustrated in the accompanying drawing in Fig. 1 is a side view, partly broken away, of my heat

treating apparatus; and Fig. 2 is a vertical section taken on the line II—II of Fig. 1.

Referring to the drawing, continuous metal strip 1 is unwound from a coil (not shown) and led over a roller 2 into one end of an insulated furnace or heating chamber 3 through a small opening 4 therein. Extending through the side walls of this chamber is a stationary horizontal shaft 6 on which a hollow strip-carrying drum 7 is journaled. The bearings for the drum may be cooled by water pipes 5 in any suitable manner. Rigidly connected to one side of the drum, as shown in Fig. 2, is a shaft-encircling sleeve 8 that projects out of the chamber and has mounted on its outer end a sprocket 9 or other suitable means for rotating the drum from any convenient power supply. The metal strip 1 is drawn into the chamber by the frictional engagement therewith of the driven drum and a roll 11 between which the strip extends and which serve as pinch rolls for this purpose. Between furnace inlet 4 and the roll the strip travels between guide plates 13 over rollers 14.

The strip is carried through the heating chamber to an outlet opening 16 in its opposite end by the drum around which the strip extends from roll 11. In initially threading the strip through the chamber its leading end is temporarily attached to the drum by any suitable means, and is disconnected therefrom when it reaches outlet 16. Access can be gained to the drum for this purpose through normally covered openings 10 and 12 in the side wall of the chamber at suitable locations. Because the drum pulls the strip into the chamber by its engagement with it at the point where roll 11 is located, no tension is placed on the portion of the strip supported by the drum ahead of that point. This permits the supported portion of the strip to be heated to a temperature at which the strip would otherwise tear apart. In order to obtain as long a heating zone as possible without placing the strip under appreciable tension, roll 11 is located at the lowest point of the drum and the heating zone for the strip extends from this point around the drum for more than three-fourths of its circumference to outlet 16 of the chamber.

The desired temperature is obtained in the furnace partly by heating the drum by electric resistors 17, connected by suitable controls, not shown, to a source of power L₁ L₂, supported close to its inner surface by an annular band 18 concentric therewith and rigidly connected to shaft 6. The rest of the heat is furnished by

electric resistors 19, connected by suitable controls, not shown, to a source of power L₃ L₄, mounted on the inner surface of an outer annular band 20 encircling the drum a short distance therefrom and secured to the side walls of the furnace. This outer band is broken at the chamber outlet and at the bottom where roll 11 is located. If desired, the inner surfaces of guide plates 13 may also be provided with electric resistors 21 for preheating the strip before it reaches the drum, but of course the temperature of the strip is not raised sufficiently during such preheating to materially affect its tensile strength.

Another feature of this invention is that the tensile strength of the strip is increased as it leaves the drum so that the increased tension which is exerted on the strip before it reaches the cooling bath in a tank 26 will not tear it. Accordingly, journaled in the entry end of the tank, which is disposed outside of the furnace below its outlet 16, is a pair of driven pinch rolls 27 one of which is entirely submerged in the bath and the other of which is partly submerged but has its upper portion extending above the tank and through furnace outlet 16 nearly into engagement with the drum. In fact, the upper roll holds the strip against the drum because it is disposed below the central horizontal plane of the drum and between diametrically opposite points on its circumference in that plane. The hot strip would otherwise hang straight down from one of those points and its weight would cause it to pull apart. Although the pinch rolls are driven at the same peripheral speed as the drum so that they will not pull the strip, the strip is subjected to some strain as it is led away from the drum down around the upper pinch roll and between the two rolls in the tank. However, the strip is strengthened so that it can withstand this strain because the upper roll is cooled by the liquid in the tank and thereby starts to reduce the temperature of the strip as soon as it engages it, which is at the point at which it leaves the drum. To hasten this cooling, nozzles 28 are positioned adjacent the opposite surface of the strip for spraying a cooling liquid thereon before it reaches the bite of the pinch rolls. From these rolls the strip loops down through the cooling liquid in the tank and passes out of it over a roller 29 at its delivery end and to driven pinch rolls 31. After the strip has been dried it can be recoiled.

To control the size of the loop in the tank so that it will not disappear and pull the strip from the pinch rolls, photoelectric cells 32 are mounted at opposite sides of the tank. If the loop in the tank starts to shorten, it permits the light beam to be established between the cells and this controls an electric circuit in well known manner which slows down pinch rolls 31 so that the size of the loop will be increased. As soon as the loop increases sufficiently to cause the light beam to be broken between the cells, the pinch roll speed will again increase.

It will thus be seen that with my invention continuous metal strip can be heat treated without danger of its being pulled apart if it is heated to a temperature at which it can not withstand appreciable tension, and that this heat treatment is accomplished in relatively small, compact and simple apparatus.

According to the provisions of the patent statutes, I have explained the principle and mode of operation of my invention and have illustrated

and described what I now consider to represent its best embodiment. However, I desire to have it understood that, within the scope of the appended claims, the invention may be practiced otherwise than as specifically illustrated and described.

I claim:

1. Heat treating apparatus comprising a heating chamber, means for carrying thin continuous metal strip therethrough under substantially no tension, means for heating the strip supported by said carrying means to a temperature at which its tensile strength is reduced to almost zero, and a cooling roll cooperating with said carrying means and around which the strip is led away from the carrying means, said roll engaging the strip at the point at which it is delivered from said carrying means.
2. Heat treating apparatus comprising a heating chamber, a drum journaled on a horizontal axis therein for carrying continuous metal strip therethrough under substantially no tension, means for heating the strip carried by the drum, and a driven cooling roll cooperating with said drum and journaled adjacent the delivery side of the drum and around which the strip is led away therefrom, the roll being spaced from the drum a distance substantially equal to the thickness of the strip.
3. Heat treating apparatus comprising a heating chamber, means for carrying continuous metal strip therethrough under substantially no tension, means for heating the strip supported by said carrying means to a temperature at which its tensile strength is reduced to almost zero, a cooling tank disposed adjacent the delivery point of said carrying means, a pair of driven pinch rolls cooperating with said carrying means associated with said tank for feeding the strip between them after it leaves the carrying means, one of said rolls engaging the strip at the point at which it leaves the carrying means, a pair of driven pinch rolls for receiving the strip from the tank, said strip forming a loop in the tank, and means for controlling the speed of the last-mentioned pair of pinch rolls to preserve said loop in the tank.
4. Heat treating apparatus comprising a heating chamber, a drum journaled on a horizontal axis therein for carrying continuous metal strip therethrough under substantially no tension, means in the chamber for delivering the strip to the drum at approximately its lowest point, means for heating the strip carried by the drum, and a cooling roll journaled adjacent the delivery side of the drum and around which the strip is led away from the drum, the strip engaging both the drum and the roll substantially at the pass between them.
5. Heat treating apparatus comprising a heating chamber, a drum journaled on a horizontal axis therein for carrying continuous metal strip therethrough under substantially no tension, means for heating the strip carried by the drum, and a cooling roll journaled adjacent the delivery side of the drum and holding the strip against the drum between its lowest point and its central horizontal plane and around which the strip is led away from the drum.
6. Heat treating apparatus comprising a heating chamber, a drum journaled on a horizontal axis therein for carrying continuous metal strip therethrough under substantially no tension, means in the chamber for delivering the strip to the drum at approximately its lowest point,

means for heating the strip carried by the drum, and a cooling roll journaled closely adjacent the delivery side of the drum less than 45° below its central horizontal plane and around which the strip is led away from the drum.

7. Heat treating apparatus comprising a heating chamber, a driven drum journaled on a horizontal axis therein for carrying continuous metal strip therethrough under substantially no tension, a roll journaled at the bottom of the drum and up around which the strip extends to the bite between the drum and roll, means for heating the strip carried by the drum, and means in close proximity to the point at which the strip leaves the drum for cooling the strip before the tension thereon becomes material.

8. Heat treating apparatus comprising a heating chamber, a driven drum journaled on a horizontal axis therein for carrying continuous metal strip therethrough under substantially no tension, a roll journaled at the bottom of the drum and up around which the strip extends to the bite between the drum and roll, means for guiding the strip to the bottom of said roll, means for heating the strip carried by the drum, and means in close proximity to the point at which the strip leaves the drum for cooling the strip before the tension thereon becomes material.

9. Heat treating apparatus comprising a heating chamber, a driven drum journaled on a horizontal axis therein for carrying continuous metal

strip therethrough under substantially no tension, a roll journaled at the bottom of the drum and up around which the strip extends to the bite between the drum and roll, means for guiding the strip to the bottom of said roll, means for preheating the strip before it reaches said roll, means for heating the strip carried by the drum, and means in close proximity to the point at which the strip leaves the drum for cooling the strip before the tension thereon becomes material.

10. Heat treating apparatus comprising a heating chamber, a drum journaled on a horizontal axis therein for carrying continuous metal strip therethrough under substantially no tension, annularly disposed heating means mounted inside of said drum, heating means encircling said drum, and means in close proximity to the point at which the strip leaves the drum for cooling the strip before the tension thereon becomes material.

11. Heat treating apparatus comprising a heating chamber, a drum journaled on a horizontal axis therein for carrying continuous metal strip therethrough, annularly disposed heating means mounted inside of said drum, heating means encircling said drum, and means in the chamber for delivering the strip to the drum at approximately its lowest point, said strip engaging the drum for at least three-quarters of its circumference.
